UNITED STATES PATENT OFFICE.

FRANCIS A. RICHMOND, OF ELMIRA, NEW YORK, ASSIGNOR TO THE FROSTILLA COMPANY, OF ELMIRA, NEW YORK, A CORPORATION OF DELAWARE.

LOTION.

No Drawing.

Application filed July 17, 1926. Serial No. 123,252.

This invention relates to lotions for personal use and pertains particularly to an improved creamy skin lotion.

The object of the invention is to provide a lotion of the usual desired creamy emollient type and which is new and advantageous because of its permanent characteristics and its ability to retain its color and physical creamy condition for long periods after preparation.

Heretofore, various creamy lotions for the skin have been marketed. Many of these have included in their compositions gums, mucilaginous materials, various emulsoid colloids such as tragacanth, acacia, and pectous substances, and such materials as glycerine, soaps, oils, almond meal, alcohol, antiseptics and perfumes. Many proprietary products which contain in their formulas some of the foregoing materials including pectous substances from various sources have, when freshly prepared, a creamy appearance or a greyish white opaque appearance when in the bottle and many have a creamy consistency as contrasted to watery consistency when freshly prepared. It has been observed that such products deteriorate by aging as evidenced by darkening, namely changing from a cream color to a dirty grey, and as evidenced by increased watery consistency as contrasted to the relatively thicker creamy consistency of the original product. Such deterioration renders the product undesirable both from the standpoint of the user and from the viewpoint of the seller, and the goods thus become unmarketable and shelf-worn goods constitute a positive financial loss.

The present invention provides a creamy emollient lotion which is peculiar in that aging apparently does not reduce its viscosity or darken it. Thus, for example, after several years the product of this invention appears substantially unchanged whereas as previously known products have darkened and become watery in a like period. The general features of the lotion of this invention include a creamy base of a somewhat flocculent character to be used in a proper combination with water for applying to the skin medicants of a cooling and soothing nature, and also substances which improve

the texture or color of the skin. The most important of these materials is the base. For many years glycerine and perfumed water have been used but a creamy base which in itself has emollient properties is a distinct improvement over a glycerine and water mixture. Consequently various emulsoid colloids such as agar-agar, tragacanth and other materials including pectous substances from various sources have been used to provide the desired creamy base, but all of these materials have been in various degrees subject to the above mentioned deterioration.

In preparing the lotion of the present invention a particular pectin base is used, namely lemon pectin and citrous pectins in substantially pure condition and to such material may be added glycerine, soaps, oils, emulsified oils, lanolin, almond oil, peach kernel oil, stearic acid, alkali stearates, almond meal, and substances of similar nature that have an emollient action on the skin. In addition there may be added such materials as boric acid, borax, alcohol and other mild antiseptics, together with tinctures of such other compounds as myrrh, orris, benzoin, tolu, styrax or other gums, and the whole may be perfumed to provide an agreeable odor. For example a lotion comprising the present invention may be made up from the following materials and in the proportions indicated:

Citrous pectin 1 part by weight.	85
Tincture benzoin 1 fluid ounce.	
Glycerine 4 parts by weight.	
Water and perfume 24 parts by weight.	
An optional mixture may be—	
Pure lemon pectin 8 parts by weight.	90
Tincture benzoin 20 parts by weight.	
Glycol 100 parts by weight.	
Boric acid 4 parts by weight.	
Water 850 parts by weight.	
Perfume to suit.	95

The invention is predicated on the use of the citrous pectin which is in substantially pure condition, indeed astonishingly pure as compared to other known forms of pectin and produced by other known processes. This peculiar pectin base has been proved susceptible to incorporation with other lotion materials and with the unexpected result that the lotion has not deteriorated. The

explanation for such resistance to deterioration has not yet been discovered, but is probably due to the temperature attained in the extraction of the pectin.

- 5 In preparing the pectin used in the lotion of the present invention the following procedure is recommended:

The lemon refuse from the manufacture of citric acid contains 2.5 to 4% pectin. This 10 refuse is cut or ground and heated to 95° to 98° C. for about ten minutes to destroy the pectinase which converts the pectin in pectin acid. The pulp is then washed in cold water on a revolving screen to remove 15 fine particles and milky liquids. The ground washed pulp is run into wood tanks having false bottoms covered with filter cloth: 1000 to 2000 lbs. is usually a charge. A one per cent solution of sulphurous acid is added in 20 sufficient quantity to suspend the pulp and the mixture is brought rapidly to about 90° C. The mixture is held at this temperature for two hours and is drawn off through the false bottom, the pulp itself making a filter 25 mat. A second or third extraction is made in the same manner. The combined extracts are filtered and the pectin solution, which usually contains about .5% pectin, is rapidly cooled and excess sulphur dioxide 30 removed by passing it over a series of baffle plates as in an ordinary water cooling tower. The solution is run into tanks of 7500 liters capacity and there precipitated by adding the proper amount of aluminum sulphate 35 and ammonium hydroxide. The ammonium hydroxide is first added and while being violently agitated the aluminum sulphate is added rapidly, the contents of the tank is now violently agitated which whips air into 40 the precipitate causing it to rise to the top in a thick spongy mass. The mother liquor is withdrawn through a screen and excess aluminum sulphate is washed from the precipitately short agitation with cold water. It 45 is finally drawn off through a screen and the excess solution removed by a centrifugal or hydraulic press. The pressed pectin precipitate is dried in a hot air dryer at about 65° C. and the dried pectin ground in a mill to 50 100 mesh. The ground crude pectin is washed with alcohol and hydrochloric acid to remove the aluminum hydrate and then washed with alcohol alone to remove the hydrochloric acid and aluminum chloride. The 55 alcohol is drawn off through a filter cloth and recovered by distillation. The washed pectin is dried at a moderate temperature in a vacuum oven and is then put through a screen for sizing and packed for market. 60 The pectin made in accordance with the foregoing procedure is nearly pure. It contains less than three per cent of ash which is made up of aluminum sulphate 1.3%, calcium sulphate .8%, and silica and silicates 65 of about .8%. Possibly the purity is due

to the method of making, namely by colloidal precipitation with subsequent washing. At any rate the product is free from oil, starch, protein and fiber, and also free from the usual citrous juices. In addition to the 70 ash content there is an additional impurity totalling less than .2% and composed of small amounts of hydrochloric acid, citric acid, and sulphurous acid. The purity of this citrous product is in contrast to the compositions of other pectins now available on the market and which are chiefly made by extracting the material with acidified water, filtering and evaporation to dryness and subsequent grinding. Such methods give products which contain pectin but also contain large amounts of impurities such as ash, protein matter, starchy matter, fiber and much coloring matter, all of which is disastrous to lotion standards. It is quite possible that 80 the citrous pectin of the present invention may contain other colloids in addition to pectin, but at present the nature and amount of such colloids is unknown.

In contrast to the citrous pectin of the 90 present invention some of the marketed pectin contains as much as 10% of impurities in the form of sodium chloride, calcium sulphate SiO_2 , silicates, coloring matter, starch, protein, and fiber.

Just exactly what active element in the citrous pectin causes the product of the present invention to remain perfect for years longer than lotions containing other pectin or containing gums is not yet proved. Various explanations have been offered but an exact and satisfactory solution to the problem has not yet been advanced.

Lemon materials have heretofore frequently been used in toilet preparations, but such use has included substantially the entire lemon including pulp, oil, starch, protein, and fiber and other such materials which have been proved ruinous to the keeping qualities of lotions and the presence of 105 which materials are incompatible with the purity and lasting qualities of the present product.

No claim is made to the specific process for extracting pure pectin from citrous fruit. The present invention is directed to the lotion which possesses peculiar properties and which includes the above described pure citrous pectin as a result of the use of which 115 some unexplainable action lengthens the 120 keepings qualities of the lotion.

I claim:

1. A lotion for personal use including a base comprising substantially pure citrous pectin.

2. A lotion for personal use including a base comprising substantially pure citrous pectin freed from the presence of other citrous materials.

3. A lotion for personal use including a 130

base comprising substantially pure lemon pectin and containing not more than 3% of ash and not more than .2% of acids. 10

4. A lotion for personal use including a base comprising substantially pure lemon pectin and containing not more than 3% of ash.

5. A lotion for personal use including a base comprising substantially pure lemon

pectin and containing not more than 3% of ash and not more than .2% of acids. 10

6. A lotion for personal use including a creamy emollient base which includes substantially pure citrous pectin containing not more than 3% of solid impurities.

In testimony whereof I affix my signature.

FRANCIS A. RICHMOND.
